CALCULATING MACHINE

Worth Arnett, Birmingham, Ala.

Application August 10, 1936, Serial No. 95,221

1 Claim. (Cl. 235—74)

This invention relates to a calculating machine and more particularly to an adding or subtracting machine of the type comprising a series of rotary indicating dials or discs adapted to be acted upon by a suitable tool such as a stylus, pencil or the like to actuate the computing mechanism.

The principal object of this invention is to provide between the dials or discs of the calculating machine each carrying a different member scale, an indicating member provided with a visible portion which is brought into view over a dial having a number scale of one character when an adjacent dial having a number scale of a different character is given a complete revolution so as to indicate to the operator when to "carry" or "borrow" depending upon whether the machine is operated for addition or subtraction.

Another object of this invention is to enable the zero position to be quickly and readily obtained in resetting the mechanism and with practically no mental effort on the part of the operator.

A further object of this invention relates to the adaptability of the same for use in computations of varying character wherein the dials may be formed to read in hours, days, weeks, months and years; fractions of an inch, inches, feet, yards, etc.; or any other number system adaptable for addition or subtraction.

A still further object of this invention relates to the simple construction of the same which is of relatively few parts, inexpensive to manufacture, which may be made small in size for carrying in a pocket, and which is accurate and dependable in operation.

Other objects of this invention will become apparent as the description thereof given hereunder proceeds with reference to the accompanying drawings wherein:—

Figure 1 is a top plan view of the calculating machine.

Figure 2 is a plan view of the interior of the calculating machine with the cover removed.

Figure 3 is a transverse sectional view taken on line 3—3, Figure 1, looking in the direction of the arrows.

Figure 4 is a plan view of a modified form of calculating machine.

Figure 5 is a detail sectional view of one end of the indicating member taken on line 5—5, Figure 2.

Referring to the several figures of the drawings, in which corresponding parts are indicated by the same reference characters, 10 indicates a

casing housing the computing mechanism which comprises see Figure 3, a base 11, a spacer 12 and a cover 13; made of any suitable rigid material such as sheet metal, fibre, cardboard, Bakelite, etc. The spacer 12 is of the same outside dimensions as the base 11 and is in the form of a gasket having long sides 14 and 15, and short sides 16 and 17, as clearly shown in Figure 2, and defines a walled recess.

Arranged in a row on the base 11 and symmetrically spaced from the sides of the spacer 12 are a plurality of rotatable number dials 20, 21, 22 and 23, each fitted on a sleeve 24 centered by an internally threaded pin 25 projecting upwardly through the base 11. The sleeves 24 are preferably made of a length exceeding the thickness of the dials 20, 21, 22 and 23 so as to project slightly above the same for a purpose to be hereinafter described. As the construction of the parts for each dial is identical, a description of the same with reference to the dial 20 shown in section in Figure 3 will be given.

Mounted on the projecting fall of the sleeve 24 is a stationary number dial 20a having a diameter less than the diameter of the dial 20, both said dials being co-axially arranged. The dial 20a is securely clamped to the sleeve 24 and base 11 by the screw 26 having threaded engagement with the pin 25. Similar stationary dials 21a, 22a and 23a are respectively mounted in a like manner in superposed relation to the rotary dials 21, 22, and 23.

Each of the rotating dials 20, 21, 22 and 23 is provided with a circular row of ten equally spaced openings 30 adjacent the peripheral edge thereof, numbered from 0 to 9 in a clockwise direction in the manner as shown in Figure 2. Opposite the numeral 9 on each rotating dial there is provided thereon a cam projection or lug 31 that extends radially outwardly from the periphery of the dial. For each rotating dial there is provided in the base 11 an opening 32, each in a plane normal to the line passing through the centers of rotation of the dials 20, 21, 22 and 23 and so positioned as to register with the openings 30 in said dials. Thus with the zero opening of each dial brought into registry with the opening 32 all of said dials will be set in their zero position preliminary to operating the machine in the manner to be hereinafter described.

The stationary dials 20a, 21a, 22a and 23a are numbered in a counter-clockwise direction from 1 to 9 with the zero position indicated by a cut-away or notched portion 34 formed on said dials. The cut-away portions 34 are made large

enough so that the numerals on the rotating dials will clearly appear therein, see Figure 1. As the latter dials are turned, the numerals thereon being completely covered by said stationary dials except as above indicated, the stationary dials **20a**, **21a**, **22a** and **23a** are positioned in an identical manner with the cut-away portions **34** arranged in opposed relation to the openings **32** in the base **11**.

10 Pivotaly arranged for oscillating movement between the rotating dials are indicators **36**, **37** and **38**. The indicators are preferably formed of very thin sheet metal having a body portion **39** provided at one end with a semi-circular flanged **15** abutment **40** and at its other end with a raised or offset indicating extension **41** of any suitable shape which may in order to increase its visibility be given any desired color. The indicators **36**, **37** and **38** are arranged in line between the **20** rotating dials, see Figure 2, and are pivotally attached to the base **11** by the screws **42**. In order to prevent the indicators from getting out of position the spacer **12** on its long side **14** is provided with integral tongues or guides **44** and **45**, with **25** the guides **44** being of greater length than the guides **45**. Thus with the indicators attached to the base **11** the spacer **12** is so arranged that the long guides **44** will extend beneath the raised indicating extensions **41** while the short guides **45** **30** will extend over the body portions **39**.

Referring to Figure 2 it will be observed that the indicators are so formed that in their normal position relative to the rotating dials, the abutment **40** will ride substantially on the periphery **35** of the rotating dial adjacent thereto while the indicating extension **41** will substantially clear the rotating dial adjacent thereto to be completely hidden beneath the cover **13** as will be hereinafter described.

40 The cover plate **13** is provided with a row of circular openings **20b**, **21b**, **22b** and **23b** of a diameter slightly less than the diameter of the rotating dials whereby when the cover **13** is applied the openings **30** in said dials will appear in **45** a circular row between the peripheral edge of said openings and the peripheral edge of the stationary dials, as clearly shown in Figure 1. Around each of said openings is provided a circular row of numerals from 0 to 9 in a clockwise direction with the zero of each row opposite the cut-away portion **34** of the stationary dials.

The base **11**, spacer **12** and cover **13** are maintained in assembled relation by the screws **48**. Referring to Figure 3 it will be observed that for **55** the sake of clarity there is shown a space between the spacer **12** and cover **13** in actual practice in view of the thinness of the same and the indicators the edges of the spacer and cover are actually brought together by the screws **48**.

60 To add, for example numbers "2165" and "3281", first with the rotating dials all in the zero setting, dial "2165" by placing a pencil or stylus in the opening of the dial **20** opposite the numeral "2" and turn the same counterclockwise **65** until the pencil engages opening **32** in base **11**. Similarly dial "1", "6", and "5" respectively on dials **21**, **22** and **23**. Then "2—1—6—5" will show in openings or cut-away portions **34** of the sta-

tionary dials. Next dial "3281" in a similar manner. Now "5—3—4—6" will show in openings **34**, with indicating extension **41** showing above the numeral "3". Place pencil in opening opposite "1" to right of indicator and turn dial **21** counterclockwise till pencil engages base opening **32**. This forces indicating extension **41** out of view and the sum of "2165" and "3281" is shown to be "5446".

For adding numerals on cover are used with **10** rotating dials turned counterclockwise always "carrying" when indicated in the manner as described above. To subtract use the numerals on the stationary dials and turn the rotating dials clockwise, "borrowing" when the indicators show. **15** Both borrowing and carrying should be done in the order of tens, hundreds, thousands.

The calculating machine shown in the modification of Figure 4 is constructed on the same principles as above set forth and is calibrated to **20** give readings in feet, inches and fractions of an inch. Thus the rotating dial A gives readings in feet in increments of ten, the dial B gives readings in feet from 1 to 9, the dial C gives readings in inches from 1 to 11, and the dial D gives readings in sixteenths of an inch from $\frac{1}{16}$ to $\frac{15}{16}$, each dial being provided with the corresponding number of openings and numerals in the manner shown. The dial settings as shown in Figure 4 gives a reading of $5'-11\frac{7}{16}''$. Addition and subtraction in feet and inches is accomplished in the same manner as described above.

Having thus set forth and disclosed the nature of this invention, what is claimed is:

In an adding and subtracting machine including a casing having a base, sides, and a cover provided with a plurality of circular openings, a pair of superposed dials arranged concentrically with respect to each cover opening and mounted on the base of said casing, the lower dial of each **40** pair being rotatable and stylus operated and the upper dial being stationary, of less diameter than the lower dial and said circular opening and in the plane of said opening to define therewith an annular opening; the combination of an indicator member disposed between each of two adjacent rotary dials, each indicator member comprising a body portion pivoted to the base of said casing, an abutment at one end of said body portion arranged in juxtaposition to an adjacent rotary dial, and a laterally offset indicating portion at the other end thereof arranged to be moved within said annular space across the other adjacent rotary dial, each rotary dial being provided with a cam lug adapted to engage the abutment of an adjacent indicator member to actuate the same, said indicator members being arranged on the same side of said dials and adjacent a side of said casing and a pair of guide members of unequal length for each indicator member fixed to **45** said casing side and extending laterally across said indicator members, the shorter of said guide members engaging the upper surface of said body portions and the longer of said guide members engaging the under surface of said indicating portion.

WORTH ARNETT.
